UNITED STATES PATENT OFFICE.

JOHN J. DAVIS AND THOMAS DUNCAN, OF MUNCIE, INDIANA.

DESIGN FOR A CHURN-DASHER.

SPECIFICATION forming part of Design No. 34,408, dated April 23, 1901.

Application filed March 18, 1901. Serial No. 51,786. Term of patent 7 years.

To all whom it may concern:

Be it known that we, JOHN J. DAVIS and THOMAS DUNCAN, citizens of the United States, residing at Muncie, in the county of Delaware and State of Indiana, have invented and produced a new and original Design for a Churn-Dasher, of which the following is a specification.

This invention relates to a new and original design for a churn-dasher, and the essential feature resides in the design as illustrated in the accompanying drawings, wherein—

Figure 1 is a front elevation of a churn-dasher embodying the design. Fig. 2 is an edge elevation thereof.

The design is characterized by a truncated conical body 1, connecting with a lower head 2, the lower head laterally projecting at opposite sides and having downwardly and in-

wardly converging straight faces 3 and 4 and vertical slots 5 opening through the lower extremity and provided with upper curved terminal walls 6 to produce three distinct elements 7, 8, and 9. The head is curved gradually into the outer edges of the elements 7 and 9, as at 10.

Having thus described the invention, what is claimed as new is—

The design for a churn-dasher, as herein shown and described.

In testimony that we claim the foregoing as our own we have hereto affixed our signatures in the presence of two witnesses.

JOHN J. DAVIS.
THOMAS DUNCAN.
